UNITED STATES PATENT OFFICE.

CHARLES H. GILLESPIE, OF BEMENT, ILLINOIS, ASSIGNOR, BY MESNE ASSIGNMENTS,
TO MAXRITE CARBURETOR COMPANY, A CORPORATION.

CARBURETER.

1,279,326.

Specification of Letters Patent. Patented Sept. 17, 1918.

Application filed March 2, 1917. Serial No. 151,949.

To all whom it may concern:

Be it known that I, CHARLES H. GILLESPIE, a resident of Bement, county of Piatt, and State of Illinois, have invented certain new and useful Improvements in Carbureters, of which the following is a specification.

My invention relates to improvements in carbureters and the principal object thereof is the provision of a device of this character which is simple in construction and efficient in operation, automatically controlling the relative proportion of the fuel and air in the mixture during changes in the speed of the motor.

A further object is the provision of a device of this character in which the fuel, hydrocarbon or the like, is properly vaporized so as to insure efficient combustion.

To the accomplishment of the foregoing and such other objects as may hereinafter appear, my invention consists in the construction, combination and arrangement of parts hereinafter described and then sought to be defined in the appended claims, reference being had to the accompanying drawings forming a part hereof and which shows for the purpose of illustrative disclosure a preferred embodiment of my invention, it being understood that various changes may be made in practice within the scope of the claims without digressing from my inventive idea.

In the drawings,—

Figure 1 represents a plan view of a device constructed according to and embodying my invention;

Fig. 2 is a horizontal longitudinal section of Fig. 1;

Fig. 3 is a vertical section on line 3—3 of Fig. 1;

Fig. 4 is a vertical cross section on line 4—4 of Fig. 1.

This invention comprises, broadly speaking, a mixing chamber adapted to receive the fuel from a suitable source of supply and having an air inlet, the quantity of fuel and air admitted to the mixing chamber being controlled by a member, the position of which is determined or adjusted by the

speed of the motor, whereby the relative proportion of the fuel and air admitted is maintained practically constant. Thorough mixture of the fuel and air and vaporization of the mixture is also obtained.

Referring now to the drawings, the numeral 1 designates the casing as a whole, having the chamber or compartment 2, adapted to receive a float, which is not shown as that feature of the construction is well known in the art. This float is used to operate a needle or other valve so as to insure the maintenance of a suitable quantity of fuel in the chamber or compartment 2. This chamber or compartment 2, which I term the fuel supply chamber or compartment, has the passage 3 which may be controlled by a needle valve leading to the mixing chamber or compartment 4. This mixing chamber or compartment 4 has the enlarged operating portion or mixing chamber proper 5, to which the outlet 6 to the motor connects, and the reduced end portion 7, both of the portions of the mixing chamber being preferably cylindrical. The reduced portion 7 of the mixing chamber is provided with a plurality or series of apertures or ports 8 in the side thereof to connect the horizontal portion 3' of passage 3 from the fuel supply chamber thereto for the admission of fuel, the end port 8' being the largest. I also provide the elongated longitudinally extending slot 9 opening into the top of the reduced portion 7 of the mixing chamber for the inlet of the air thereto, as will presently be described.

Movably mounted in the mixing chamber is the controlling member 10, which is in the form of a double piston element, normally held in the position shown. It comprises the rod or shaft 11 having the large piston 12 secured on the end in the mixing chamber proper and having the smaller piston 13 secured on the end positioned in the reduced portion 7 of the mixing chamber, as shown. These pistons 12 and 13 are held in place by means of the screw threaded ends 14 of rod or shaft 11 engaging them and having jam nuts 15 thereon. The casing is provided with the caps 16 and 17, for

assembling, inspection and repair, the cap 16 being provided with a plurality of apertures 16' for the admission of air.

Coil spring 18 engages larger piston 12 and the shoulder of flange 19 in the mixing chamber or compartment for holding the controlling member in the position shown and permitting it to move under the pressure of the air admitted against the end of the large piston, the movement being controlled by the suction from the motor when running, so that the position of the controlling member is varied according to the speed of the motor or the work it is doing. Smaller piston 13 is provided with the laterally extending cut-off plate or extension 20 fitting over the slot 9 through which the air is admitted and serves as a cut-off to control the amount of the air admitted into the mixing chamber. In the reduced portion 7, I form the stop flange or abutment at 21 for limiting the inward movement of the smaller piston. This stop or abutment and the cut-off member 20 are so arranged relatively that when the smaller piston reaches the limit of its inward movement due to the action of the spring, the cut-off member will cover that portion of the air admission slot leading into the mixing chamber, and the end port or aperture 8 will open into the mixing chamber. This results in "choking" the carburetor, so that a rich charge or mixture is left in the cylinders for starting and also a rich fuel mixture will be drawn in during the starting of the motor, the cut-off member 20 preventing the admission of air. But as soon as the engine starts, the controlling member moves outwardly under the influence of the air pressure against the larger piston due to the reduction of the pressure against the inner side thereof on account of the suction of the engine. A small air vent 22 is provided for proper operation of the device. The adjusting screw 23 may be utilized in the larger cap 16.

The operation of the device is as follows, it being recalled that a quantity of the fuel is present in the chamber 2. The suction from the motor decreases the pressure against the inside of piston 12 and allows the atmospheric pressure against the other side to overcome the pressure of the spring element 18, causing the controlling member 55 to move to the left, looking at Fig. 2 of the drawing, so that more of the fuel inlet ports 8 are uncovered or opened and so that a larger or longer portion of slot 9 is opened into the mixing chamber, thereby admitting 60 more fuel as well as more air, so that the relative quantities of fuel and air admitted remain practically constant due to the movement of the controlling member under the influence of the motor and atmospheric pressure. The fuel and air are admitted

in the same portion in the mixing chamber, so that they are readily mixed together before passing out through the outlet to the inlet manifold or other supply to the motor.

It is therefore seen that I have provided 70 a device which is exceedingly simple in construction and efficient in operation, maintaining the same relative proportion of the air and fuel admitted to the carburetor and causing the same to be vaporized before 75 passing to the intake manifold, resulting in greater efficiency. Necessary adjustments may be made by varying the spring, the size of the ports 8 and slot 9, and also by the screw 23 in the cap 16. 80

What I claim is:—

1. A device of the character described including in combination a float chamber, a mixing chamber or compartment having two cylindrical portions, one of said portions having an elongated slot along its top for the admission of air thereinto, a passage extending from said float chamber and along the top edge of said cylindrical portion formed by the said slot and having a 90 plurality of inlet ports leading from said passage into the upper part of said cylindrical portion, a controlling member in said mixing chamber or compartment comprising a pair of pistons mounted for movement together, one of said pistons fitting in each cylindrical portion, the said piston in the cylindrical portion having a slot being provided with an extension adapted to fit over said slot, resilient means for normally holding said controlling member in a position to admit a minimum quantity of fuel into the mixing chamber, said extensions serving to control the admission of air and the piston to which it is connected, serving as 100 a cutoff to control the admission of fuel into the mixing chamber or compartment. 105

2. A device of the character described including in combination a float chamber, a mixing chamber or compartment having two cylindrical portions, one of said portions having an elongated slot along its top for the admission of air thereinto, a passage extending from said float chamber and along the top edge of said cylindrical portion formed by the said slot and having a 115 plurality of inlet ports leading from said passage into the upper part of said cylindrical portion, a controlling member in said mixing chamber or compartment comprising a pair of pistons mounted for movement together, one of said pistons fitting in each cylindrical portion, the said piston in the cylindrical portion having a slot being provided with an extension adapted to fit over 120 said slot, resilient means for normally holding said controlling member in a position to admit a minimum quantity of fuel into the mixing chamber, said extension serving to control the admission of air and the piston 130

to which it is connected serving as a cut off to control the admission of fuel into the mixing chamber or compartment, and means to limit the inward movement of said pistons so that when they are at the end of said inward movement the portion of said air admission slot opening into the mixing chamber is closed by said extension and certain of said fuel supply ports are open into the mixing chamber so that an unrarefied supply of fuel may be drawn into the mixing chamber in starting. 10

CHARLES H. GILLESPIE.
